(57) **CLAIM**

I claim the ornamental design for a toilet paper cabinet, of the present invention.

DESCRIPTION

The present design relates to a cabinet for holding rolls of toilet paper in storage until they are needed to be used on an integrally mounted toilet paper roller. The toilet paper cabinet of the present invention includes one embodiment that is free-standing and a related design that is integrally mounted within a partition or wall.

FIG. 1 is a front elevational view of the toilet paper cabinet of the present invention.

FIG. 2 is a rear view of the toilet paper cabinet as depicted in FIG. 1.

FIG. 3 is a left side view of the toilet paper cabinet as depicted in FIG. 1.

FIG. 4 is a right side view of the toilet paper cabinet as depicted in FIG. 1, with rolls of toilet paper (in phantom) shown as they would be installed.

FIG. 5 is a top view of the toilet paper cabinet as depicted in FIG. 1.

FIG. 6 is a bottom view of the toilet paper cabinet as depicted in FIG. 1; and,

FIG. 7 is an isometric view of the toilet paper cabinet of the present invention in accordance with FIG. 1.
